Primary Examiner — Mitchell I. Siegel(74) *Attorney, Agent, or Firm* — Caesar Rivise, PC(57) **CLAIM**

The ornamental design for the golf club head, as shown and described.

DESCRIPTION

FIG. 1 is a top, isometric view of a golf club head showing my new design;

FIG. 2 is a bottom, isometric view of the golf club head of FIG. 1;

FIG. 3 is a rear elevation view of the golf club head of FIG. 1;

FIG. 4 is a front elevation view of the golf club head of FIG. 1;

FIG. 5 is a top plan view of the golf club head of FIG. 1; FIG. 6 is a bottom plan view of the golf club head of FIG. 1;

FIG. 7 is left side elevation view of the golf club head of FIG. 1;

FIG. 8 is a right side elevation view of the golf club head of FIG. 1; and,

FIG. 9 is a cross-sectional view taken along line 9-9 of FIG. 5.

The features shown in broken lines in the drawing depict portions of the design that form no part of the claimed design.

1 Claim, 5 Drawing Sheets# US D834,662 S
